CLAIM

The ornamental design for a plant pot, as shown and described.

DESCRIPTION

FIG. 1 is a perspective view of a plant pot showing our new design;

FIG. 2 is a front elevation view thereof;

FIG. 3 is a right side view thereof;

FIG. 4 is a top plan view thereof;

FIG. 5 is a bottom plan view thereof; and,

FIG. 6 is another perspective view thereof.

The broken lines are included for the purpose of showing portions of the plant pot that form no part of the claimed design.

1 Claim, 4 Drawing Sheets
